THREAD GRINDING MACHINE

Fernand Turrettini, Geneva, Switzerland, assignor to Societe Genevoise D'Instruments De Physique, Geneva, Switzerland, a firm of Switzerland

Application March 27, 1945, Serial No. 585,048
In Switzerland August 23, 1944

6 Claims. (Cl. 51—95)

1

The present invention relates to thread grinding machines, and in particular to machines of the type comprising a grinding wheel mounted on a carriage slideable at a right angle to the axis of the work piece under the action of a first adjusting device, a truing tool mounted retractably in front of the grinding wheel on a first support mounted rotatively on said carriage around an axis parallel to the direction of motion of the latter, the grinding wheel being carried by a second support mounted rotatively around the axis of rotation of the first support and slidably along this common axis, and a second adjusting device inserted between the first and the second support for moving the grinding wheel in a direction parallel to that of said carriage, with the object that the distance from the cutting edge of the grinding wheel to the axis of the work piece remains permanently determined by the indications of the first adjusting device, independent from the quantity of abrasive removed from the grinding wheel.

The advantage of this machine is that the operator can carry on its thread grinding work without the necessity of frequently interrupting it for measuring the workpiece, the micrometric adjustment of the wheel supporting carriage giving always an accurate reading of the position of the wheel's cutting edge in respect with the workpiece, independently from the wear of the wheel.

The annexed drawing represents by way of example one constructional form of the machine according to the invention.

The machine according to the invention, of the type mentioned above, eliminates all these difficulties. It is characterized in that the truing device, which operates in front of the grinding wheel, is retractably arranged on a first support enabling to clear the grinding wheel, said support being borne by a carriage in such a manner as to be dependent on the latter in the direction of the travel of this carriage and, in the same time, rotating on itself in order to adjust the inclination of the plane in which the truing has to be performed, the grinding wheel being carried by a second support concentric with the first one and arranged to rotate on itself in such a manner that the grinding wheel may be adjusted tangentially to the helices of the thread to be ground and that it also may move in a direction parallel to said travel, under the action of a second adjusting device inserted between the first and the second support, with the object that the distance from the active face of the grinding wheel to the

2

axis of the work piece remains permanently determined by the indications of the first adjusting device, independent from the quantity of abrasive removed from the grinding wheel.

The annexed drawing represents by way of example one constructional form of the machine according to the invention. The Fig. 1 is a transverse section; the Fig. 2 is a section through II—II and the Fig. 3 a section through III—III of the Fig. 1. The Fig. 4 is a front elevation.

In all these figures, 1 is the bed of the grinding machine comprising a slide 2 extending at right angle to the longitudinal slides 3 and 3a of the bed; the slide 2 extends towards the rear of the machine and bears the carriage 4. The table 5 and the axis of the work piece to be ground is 6, the work piece itself being 6'. The work piece moves with the table on the bed by means of the spindle 7, as well as by means of other members not shown.

The grinding wheel is 8, its axis is 9; the latter is being driven by the pulley 10. The truing diamond is 11, its point of contact with the grinding wheel is on the horizontal axis A—A at right angle to the axis of the work piece to be ground and passing through the centre of the grinding wheel. The arm 12, carrying the diamond, is fixed on trunnion pin 13. The diamond 11 trues-up the two flanks of the active face of the grinding wheel by an oscillatory movement of small amplitude about said trunnion pin. The oscillatory movement is produced by means not shown on the drawing.

The trunnion pin 13 revolves in a head 14 dependent on a shaft 15 which may, by rotating in a bearing 16, describe the angle α comprised between the flanks of the active face of the grinding wheel. The bearing 16 forms part of an arm 17 rigidly fixed by screws 18 and 19 on extensions 20 and 21 of a hollow cylinder 22 rotating in bearings 23 and 24 belonging to a sleeve 25 fixed to the carriage 4.

This rotary motion, obtained by the action of a worm screw 26 engaging a toothed sector 26' fixed to the sleeve 25, serves to adjust the plane of inclination in which the diamond 11 has to carry out the truing-up. The worm screw 26 rotates in bearing 27 and 28 dependent on the arm 17. The group consisting of pieces 16, 17, 20, 21 and 22 forms the first support which moves with the carriage 4 with respect to the axis 6 and the work piece 6' through the action of a handle 29 dependent on a graduated wheel 30; the latter is fixed on a shaft 31 comprising at its extremity

a threaded portion 32 engaged with the nut 33 dependent on the carriage 4.

A second support is arranged concentrically with the hollow cylinder 22; it is formed by the tube 34 ending at the extremity facing the work piece by a flange 35 fixed rigidly on the tube and carrying the bearing 36 containing the axis 9 of the grinding wheel 8. The tube 34 bears at its rear a flange 37 on which is fixed the motor 38 driving the grinding wheel.

The second support 34 may rotate about the axis A—A under the action of a toothed sector 39 with straight teeth engaging with a circular rack formed by a tube 40 provided with parallel grooves 41 showing the profile of a rack.

The tube 40 is fixed axially on a shaft 42 on which it may freely rotate due to the ball bearings 43 and 44. The shaft 42 may move axially by means of a screw 45 engaging with a nut 46 fixed in a recess 47 on the shaft 42. The rotation of this screw is effected by the action of a wheel 48 provided with a handle 49 and with a graduation 50. The group consisting of pieces 39, 41, 42, 45, 46, 49 and 50 has the object of adjusting the grinding wheel tangentially to the helices of the thread to be ground on the piece 6'. The tube 34 with all the pieces which it carries (second support) has to move axially in the hollow cylinder 22 (first support) in order to bring the grinding wheel 8 in contact with the diamond 11 in such a manner that the truing operation re-conditions the profile of the active edge of the grinding wheel. This axial movement is obtained by means of a second adjusting device formed by a handle 51 dependent on a shaft 52, meshing by the gear 53 with a shaft 54, the bearing 54' of which is dependent on the arm 17. The shaft 54 transmits its rotary motion to the gear 55 by means of universal joints 56 and 57. The shaft of the gear 55 is provided with an extensible part 55a to allow for the rotation of support 34 around the axis A—A. The rotation of 55 drives the pinion 58 dependent on a screw 59 forming part of a shaft 60, which is supported on one hand by a bearing 61 fixed as well as the nut 62 on the flange 37 and consequently on the tube 34 and the grinding wheel 8 which it carries, and on the other hand, by a ball bearing 63 arranged in a piston 64 which moves in the tube 34 and resting at 65 on a rod 66 housed 67 and 68 in the hollow cylinder 22.

A spring 69 thrusting on one hand on a circular abutment 70 arranged to rotate in the piston 64, and, on the other hand, on a lid 71 fixed to the tube 34, constantly forces the grinding wheel towards the diamond. The adjusting screw 59 is opposed to the pressure exerted by the spring because it indirectly thrusts on the hollow cylinder 22, which is fixed axially. The rotation of the shaft 60 thus enables bringing the grinding wheel in contact with the diamond.

It is by no means necessary that the amplitude of the travel imparted to the grinding wheel by the second adjusting member to be taken into consideration, measured or checked in any way in a machine working according to the invention. This travel may be of any length, provided that it is sufficient to bring again the profile of the grinding wheel into contact with the diamond in such a manner that the action of the latter re-conditions the surface of the grinding wheel.

The second support 34 has therefore to rotate and to slide in the first cylinder 22; it is important that these movements are effected with a minimum of friction in order not to reduce the sen-

sibility of the adjustments. For this reason, the sets of balls 72 and 73 inserted between the hollow cylinder 22 and the tube 34 have to support and to guide the latter, the balls being able to roll in all directions enabling said pieces to carry out relative rotary and translatory movements. The sets of balls are arranged at the two extremities of the tube 34 and are formed by two elements 72a and 72b (for the train 72), separated from each other by an angle b sufficiently large to decompose the weight P of the tube 34 into two divergent components P_1 and P_2 which prevent any de-centring movement in the direction B—B. This arrangement of balls produces an effect similar to that of usual prismatic guide ways and has the advantage of enabling movements with a minimum of friction. The arm 12, which carries the diamond 11, may carry out an additional rotary motion about the trunnion pin 13 and thus may be brought into the retracted position when not in use, as shown on Fig. 4, in which position it enables the grinding wheel to come freely into contact with the work piece to be ground. The arm 12 may be maintained in this position by a retaining member 75.

If it is required to grind threads or taps, the axis C—C has to be vertically adjusted by means of the worm screw 26. If, on the other hand, milling cutters for gears have to be ground, where the characteristic profile is to be at right angle to the helices, the axis C—C has to be maintained in the same plane as that of the grinding wheel 8, plane which is tangent to the helices of the work piece to be ground. This result will be obtained by means of the worm screw 26 and the rotating rack 40.

The machine described enables maintaining the active edge of the grinding wheel immobile in space during the operation of truing-up carried out by a tool borne on a slide, the distance of which from the axis of the work piece being constantly controlled by means of an adjusting member 29, 30, dependent on the bed of the machine. The truing tool acts at the point of contact of the grinding wheel with the work piece, so that a definite relation of the position of the slide with respect to the axis of the work piece, when the latter will reach the prescribed dimensions, may be ensured. This relation will be given by the adjusting member mentioned above.

The movable parts 11, 12 of the truing member, which may form an obstacle to the contact of the work piece with the grinding wheel, may be retracted in order to permit such a contact.

Thus, the machine described does away with the necessity of measuring the work piece during the grinding operation; it further makes it possible to grind either threads with the characteristic profile being in a plane containing the axis of the work piece (in the case of screws and taps) or in a plane at right angle to the helix of the thread (in the case of gear milling cutters).

What I claim is:

1. A thread grinding machine comprising a grinding wheel mounted on a carriage slidable at a right angle to the axis of the work piece under the action of a first adjusting device, a truing tool mounted retractably in front of the grinding wheel on a first support mounted rotatively on said carriage around an axis parallel to the direction of motion of the latter, the grinding wheel being carried by a second support mounted rotatively around the axis of rotation of the first support and slidably along

this common axis, and a second adjusting device inserted between the first and the second support for moving the grinding wheel in a direction parallel to that of said carriage, with the object that the distance from the cutting edge of the grinding wheel to the axis of the work piece remains permanently determined by the indications of the first adjusting device, independent from the quantity of abrasive removed from the grinding wheel.

2. Machine according to claim 1, characterized in that the truing tool is carried by an oscillating arm mounted on the first support in such a manner that it is possible to bring it into a retracted position by an oscillation of sufficient amplitude.

3. Machine according to claim 1, characterized by the fact that the second support comprises cylindrical parts passing through a cylindrical bearing of the first support, sets of balls being inserted at these spots between the two supports in order to enable the second support to rotate and to travel axially in the first one, without harmful friction, whereby the grinding wheel can be inclined in accordance with the lead of the thread to be ground.

4. Machine according to claim 1, characterized by four sets of balls arranged by pairs at the extremities of cylindrical bearing surfaces between the first and the second support, the two sets of each pair being spaced apart from one 30

another, in order to produce an effect of prismatic guiding excluding all radial or lateral play of the second support, by means of the action of its own weight.

5. Machine according to claim 1, characterized by the fact that the rotary motion of the second support is obtained by means of a toothed sector dependent on said second support and which is engaged with a circular rack rotating freely on a shaft carried by the first support and which may travel axially by means of an adjusting member, determining the angle comprised between the plane of the grinding wheel and that in which the truing-up is carried out.
- 10 6. Machine according to claim 1, characterized in that the second support also carries the motor driving the grinding wheel.
